[57] CLAIM

The ornamental design for a combined bottle and cap, as shown and described.

DESCRIPTION

FIG. 1 is a top, front and right side perspective view of a combined bottle and cap showing our new design; FIG. 2 is a rear elevation thereof; FIG. 3 is a right side view thereof, the left side view being a mirror image thereof; FIG. 4 is a top plan view; FIG. 5 is the bottom plan view; FIG. 6 is a rear elevation of the bottle shown without the cap for clarity of illustration; and, FIG. 7 is a top plan view of FIG. 6.

FIG. 2

FIG. 5

FIG. 6

FIG. 7
